PORTABLE VISIBLE INDEX

Application filed June 27, 1930. Serial No. 464,165.

The present invention relates to visible indexes and embodies, more specifically, an improved portable type of visible index by means of which a plurality of interconnected sections may be utilized to support the desired indexing elements, the number of sections and elements carried by each being variable at will. In applicant's copending application for visible index, Serial No. 430,186 filed February 21, 1930, there is described a visible index by means of which a plurality of index card supporting sections are hinged together in the manner of the leaves of a book, the indexes being protected by such leaves and being readily moved to a suitable exposed position or protected position by opening or closing the said leaves. The interchangeability of elements, together with the ability to increase the capacity of the index, are features which will be readily apparent.

In the visible index described and claimed herein, the structure includes, basically, the features embodied in the construction shown and described in the above identified application and embodies, additionally, certain protective features which increase the serviceability and convenience of the index, as well as materially protect the indexing elements.

Accordingly, an object of the present invention is to provide a visible index, the index-supporting sections of which may be conveniently secured together in such manner that the sections may be readily taken down or assembled to include a greater or a fewer number of index-supporting sections.

A further object of the invention is to provide a means for preventing relative movement of the supporting sections towards each other beyond a predetermined limit to prevent marring of the index elements due to sliding of portions thereof over other portions.

A further object of the invention is to provide an improved hinge connection between the component parts of a visible index, the connection being of such character as to prevent lateral movement of one section with respect to the other and restraining the sections to pivotal movement only.

A further object of the invention is to provide means for readily and detachably connecting a plurality of sections of a visible index, such sections being retained effectively in an assembled relation against displacement.

Further objects, not specifically enumerated above, will be apparent as the invention is described in greater detail in connection with the accompanying drawings, wherein:

Figure 1 is a plan view showing an index constructed in accordance with the present invention and moved to its opened position.

Figure 2 is a view in end elevation, showing the index of Figure 1.

Figure 3 is a view similar to Figure 2, showing the sections moved to a closed position.

Figure 4 is an enlarged segmental view, similar to Figure 2, showing the manner of connecting adjacent sections.

Figure 5 is a view similar to Figure 1, showing the index capacity increased by the insertion of an intermediate supporting member formed of two standard supporting members placed back to back.

Figure 6 is a view similar to Figure 2, showing the index of Figure 5.

Figure 7 is a view similar to Figure 3 showing the index of Figure 5.

Figure 8 is a view in isometric projection showing a hinge member in detail.

Referring to the above drawings, *a* designates a tray which is shown as being formed of metal although any other suitable substance may be employed. As described in the above identified pending application, this tray is provided with securing means *a'* by means of which suitable index elements, such as cards *a''*, may be secured to the trays.

In the device shown in Figures 1, 2, and 3, two trays, as described above, are utilized, being hinged together at an edge of each by a hinging device which will be described more specifically hereinafter. If the trays are formed of metal, the top, bottom and one side edge may be rolled to form a suitable head *a''*. The edges to be joined may also be rolled to form beads *a''*. The ends of the beads *a''* and *a''* are preferably hollow, the ends of

the beads a^3 carrying detents b which are forced outwardly by means of springs b' . The detents are formed with rounded noses and are retained in position by partially up-
5 setting the ends of the beads as at a^5 after the detents have been inserted therein.

To facilitate the hinging of the trays together, a double hinge pin c with a U-shaped connecting portion c^2 is provided, the U-shaped portion of the member being formed with outwardly extending portions c' , lying in the plane of the parallel portions of the member and terminating in pintle portions which lie perpendicular to the plane of the parallel arms of the U-shaped member. The U-shaped portion c^2 includes parallel arms c^3 which serve as spacing members for the trays as described hereinafter.

To assemble the device as shown in Figure 20 1, two trays a are secured at opposite ends by means of two hinge members c . The pintles of these members are inserted in the ends of the beads a^4 and pressed inwardly until the detents b snap over the rounded shoulders 25 formed by the portions c' . The trays are thus assembled in book form and may be opened or closed at will. In their closed position the trays are spaced positively apart as clearly shown in Figure 3, by means of the parallel arms c^3 . Not only do these arms prevent the trays from rubbing against each other, but they also afford lateral stability against movement of the adjacent trays in their own planes, thus preventing lateral 30 rubbing of the index elements carried by the respective trays. It will be readily seen that movement of the upper tray, to the left, as viewed in Figure 3, in its own plane and 35 parallel to the lower tray, will tend to force the inwardly extending U-shaped portion c^2 upwardly, or in a counterclockwise direction with respect to the beads a^4 . The extension will thus engage the upper tray and such movement will be prevented effectively. 40 Movement in the other direction will correspondingly be prevented and the trays will be held in parallel relation and thus be prevented from collapsing or rubbing together.

Where it is desired that the index have 45 additional capacity, two trays a may be secured back to back as by spot-welding to constitute a unit d as shown in Figure 7. The beads a^4 of the unit d are thus adapted to receive the hinge members c of the outer trays a , all of the trays being prevented from 50 contacting and rubbing by means of the hinges as described in connection with the construction shown in Figure 3.

From the foregoing, it will be seen that a 55 visible index is provided, the elements of which are completely standardized, each element being simple in construction and readily assembled with the cooperating elements of the device and a standard form of hinge member being applicable to the standard form of

tray utilized. In addition to serving as an effective hinging mechanism which is readily applied and taken down, the hinge members effectively stabilize the trays when the latter are mounted to form a visible index, either 70 in the forms shown in Figures 1 and 5, or in any form including added trays.

While the invention has been described with specific reference to the accompanying drawings, it is not to be limited, save as defined in the appended claims.

I claim as my invention:

1. As an article of manufacture, a hinge member having parallel pintles, inwardly extending portions at one of the ends thereof, and a U-shaped offset portion connecting the inwardly extending portions and lying in a plane at right-angles to the pintles.

2. As an article of manufacture, a hinge member having parallel pintles, inwardly extending portions thereon, and an offset portion connecting the inwardly extending portions.

3. In combination with a plurality of trays formed with hinge-receiving apertures at adjacent sides thereof, a hinge member having parallel pintles to engage the apertures, inwardly extending portions on the pintles, and a U-shaped offset portion connecting the inwardly extending portions and lying in a plane at right-angles to the pintles.

4. In combination with a plurality of trays formed with hinge-receiving apertures at adjacent sides thereof, a hinge member having parallel pintles to engage the apertures, inwardly extending portions on the pintles, and an offset portion connecting the inwardly extending portions.

5. In combination with a plurality of trays formed with hinge-receiving apertures at adjacent sides thereof, a hinge member having parallel pintles to engage the apertures, and an offset portion connecting the pintles at one of the ends thereof and lying between the trays.

6. In combination with a plurality of trays formed with hinge-receiving apertures at adjacent sides thereof, a hinge member having parallel pintles to engage the apertures, and an offset portion connecting the pintles and lying between the trays.

7. In combination with a plurality of trays formed with hinge-receiving apertures at adjacent sides thereof, a hinge member having parallel pintles to engage the apertures, and means between the pintles to prevent lateral movement of one of the trays with respect to the other.

8. In combination with a plurality of trays formed with hinge-receiving apertures at adjacent sides thereof, a hinge member having parallel pintles to engage the apertures, and means between the pintles to space the trays.

9. An index-carrying tray formed of pressed metal and having beads formed along

a plurality of edges, a hinge member engageable in one of the beads, and a spring-pressed detent mounted in another of the beads to engage the hinge member in the other bead.

5 10. In combination with an index indicia carrying means and hinging means therefor, beads formed on the index-carrying means along adjacent intersecting edges thereof, a spring-pressed detent in one of the beads, and
10 a turned-over portion at the extremity of the last-named bead to retain the detent in position.

11. In combination with an index indicia carrying means and hinging means therefor, 15 beads formed on the index-carrying means along adjacent intersecting edges thereof, and a spring-pressed detent in one of the beads.

12. In combination with an index indicia carrying means and hinging means therefor, 20 a recess in the first means to receive the hinging means, and a spring-pressed pawl carried by the first means to maintain the hinging means normally in position.

13. A plurality of index indicia-carrying 25 members, means to connect the members hingedly, and means on the hinge means extending between the index-carrying means when the latter are closed to prevent lateral movement therebetween.

30 This specification signed this 24 day of June, A. D. 1930.
